(57) **CLAIM**

The ornamental design for a serving tray as shown and described.

DESCRIPTION

FIG. 1 is a top perspective view of a serving tray in a condition of use, showing my new design.

FIG. 2 is a bottom perspective view thereof.

FIG. 3 is a top view thereof.

FIG. 4 is a bottom view thereof.

FIG. 5 is a left side view thereof.

FIG. 6 is a right side view thereof.

FIG. 7 is a front view thereof; and,

FIG. 8 is a back view thereof.

The portion shown in broken dash lines in the Figures is for the purpose of illustrating environmental matter and forms no part of the claimed design.

1 Claim, 6 Drawing Sheets(56)
